UNITED STATES PATENT OFFICE.

WILLIAM STEPHENSON, OF MORRIS, CANADA.

COMBINED TRACTION-ENGINE AND THRESHER.

SPECIFICATION forming part of Letters Patent No. 687,868, dated December 3, 1901.

Application filed March 17, 1897. Renewed April 1, 1901. Serial No. 53,949. (No model.)

To all whom it may concern:

Be it known that I, WILLIAM STEPHENSON, a subject of the Queen of Great Britain, residing at Morris, in the county of Provincier, Province of Manitoba, Dominion of Canada, have invented certain new and useful Improvements in a Combined Traction-Engine and Thresher, of which the following is a specification, and for which I have obtained

Letters Patent in the Dominion of Canada on the 28th day of January, 1896, No. 51,157.

The object of this invention is to produce a thresher which contains within a single structure the mechanism necessary to move it not only from place to place, but to drive it over the field to be threshed, the thresher at the same time being in operation. I am enabled by my present invention to drive over a field and gather the grain thereon upon the thresher in passing. Thereby the expense attendant upon hauling the straw and grain to a stack-yard preparatory to threshing is avoided, as well as the danger of fire incident to the use of an engine adjacent to the stacks.

My invention consists in the construction, arrangement, and combination of parts hereinafter more fully described and claimed, whereby a stable mounting of the parts is secured in a simple manner.

Referring to the accompanying four sheets of drawings, which form a part of this specification, Figures 1 and 2 are elevations of a thresher constructed in accordance with this invention, taken from the right and left sides, respectively. Fig. 3 is a front view thereof. Fig. 4 is a transverse vertical section on line xx of Figs. 1 and 2 looking rearward. Fig. 5 is a longitudinal vertical section taken through the center of the fire-box and boiler.

The several parts are carried upon traction-wheels 1 1 and the forward guide-wheels 2 2, the axles 3 and 4 of which carry a suitable horizontal boiler 5 and fire-box mounted above and between the wheels. The axle 3 is mounted in brackets 3^a, which project forwardly from the fire-box. The boiler has mounted on the top thereof cylinders 6, in which are contained pistons connected to and driving the crank-shaft 7, mounted in bearings 8, which project upwardly from the boiler-shell. A pinion 9 upon one end of the shaft

7 gears with the gear-wheel 10. A second pinion 10^a, secured upon the axle of the gear-wheel, engages with and drives a gear-wheel 11, which is mounted on a transverse shaft 12. This shaft is mounted in bearings 13, pendent from the shell of the boiler. Suitable pinions 12^a are secured to each of the opposite ends of the shaft 12. These mesh with internal racks 1^a within the rims of the traction-wheels 1. Thus the traction-wheels are driven from the crank-shaft 7. The crank-shaft 7 has also mounted thereon on its opposite ends the pulleys 14^a and 15^a. Over the pulley 14 passes a belt 14^b, which drives a rotary fan 14 to supply a forced draft to the fire-box. The pulley 15^a, as will hereinafter be fully explained, drives the thresher 15.

The axle 3 of the traction-wheels projects at each end beyond the hubs of the wheels. Its projecting ends support brackets 3^a, which carry uprights 16 16^a, one on each side. The brackets in turn carry side extensions of the platform. The extensions upon the right side consist of a tank 17, which contains the water for the boiler, the tank being hung from the top of the upright 16 by links 17^a. The left extension of the platform is larger than that upon the right, its outer edge resting on a sill 18, braced by a truss 18^a. This sill is carried at its opposite ends on pendent arms 19 19^a, supported from the outer ends of the beams 20 20^a. The beam 20 projects from a forward standard 21, rigidly secured to a forward extension 5^a of the boiler. The beam 20^a rests upon the upright 16^a, the inner end of the beam being secured in any desired manner to the boiler-shell. Outside of the sill 18 and platform of the thresher is a guard-rail 18^b, which affords a convenient standing-place for the operator in working around the thresher. To reinforce the connection between the standard 21 and the beam 20 and to give sufficient strength to the latter with a minimum of weight, the standard and the beam cross each other. The end 21^b of the standard is connected with the outer projecting end of the beam 20 and with the opposite end 20^b thereof by the rods 22 and 22^a, respectively, while the end 20^b of the beam is also connected to the lower portion of the standard by the rod 22^b. In a similar manner the beam 20^a is strengthened by the rods

23 23^a, which extend from the ends of the beam to the top of the upright 16^a, carried by the bracket 15. The upright 16 has its upper end tied to the boiler by the rod 23^b, so that the platform thus carried on the sill 18 and sill 18^b, supported at the base of the upright 16^a and by the lower beam 20^c, and the mechanism therein, is balanced by the water-tank on the opposite side of the engine.

10 Upon the left platform I mount a threshing mechanism 15, of any improved construction. A belt 24 passes from the pulley 15^a on the crank-shaft to a counter-shaft 24^a, secured to the forward beam 20. From the 15 counter-shaft the thresher is driven by a belt 25. A suitable dynamo 26, driven from the counter-shaft by a belt 26^a, may be mounted upon the boiler to supply current to a lamp 27 for night-work. It is to be understood 20 that proper clutches or loose pulleys on the counter-shaft may be added, whereby all the parts may be driven together or any one or more of them disconnected while the other parts are driven. It is to be understood also 25 that I prefer to use some suitable type of straw-burning engine, so that the straw from which the grain has been separated in the thresher may be used as fuel to furnish the necessary power instead therefore of bringing 30 the grain to a stationary thresher, as is now usually done. The thresher moves over the stubble-field upon which the grain has been cut and gathers the crop and threshes the grain in passing. The above-described 35 method of mounting the several parts results in a compact structure well balanced and easily moved, controlled, and steered.

By preference I use the form of boiler shown 40 in the annexed drawings. It is a boiler having at one end a pendent water-leg 25^a. In this is contained the fire-box 26, having an aperture 26^b, its lower end closed by the ash-pan 26^a, a combustion-chamber 27, extending from the fire-box within the boiler and having 45 an enlargement 27^a, provided with an open bottom, and an ash-pan 27^b, the return-flues 28 extending from the enlargement 27^a to the smoke-stack 29. As will be noticed, the ash-openings in both the fire-box and combustion-chamber are made through the double bottom thereof, the space between which

is in communication with and forms a part of the water-space of the boiler. By this construction I provide an efficient straw-burning engine, the combustion-chamber of which 55 may be readily cleared of the ashes incident to the use of straw as a fuel, and I utilize to the fullest extent the heat resulting from the combustion of the straw.

Having thus described my invention, what I claim as my invention is—

1. The combination with driving-wheels and an axle therefor, of an engine mounted on the axle and imparting motion to the wheels, posts carried on the ends of the axle 65 outside of the wheels thereon, a beam carried by one of the posts and having one of its ends secured to the engine, a platform hung from the opposite end of the beam, and a thresher carried on the platform and driven by the 70 engine, substantially as described.

2. The combination with driving-wheels, and an axle therefor, of an engine mounted on the axle and imparting motion to the wheels, a post carried on each end of the axle outside 75 of the wheels, a beam carried by one of the posts and having its inner end tied to the engine, a thresher supported by the outer end of the beam and driven by the engine and a water-tank carried by the opposite post, the 80 upper end of which is tied to the engine, substantially as described.

3. The combination with driving-wheels, and an axle therefor, of an engine mounted on the axle and imparting motion to the wheels, 85 an upright attached to the head of the engine, a beam projecting to one side therefrom, a post carried on each end of the axle, outside of the wheels thereon, a beam carried by one of the posts, and having its inner end tied to 90 the engine, a thresher supported by the outer ends of the two beams and driven by the engine and a counterpoise for the thresher carried by the opposite post, the upper end of which is tied to the engine, substantially as 95 described.

Signed by me at Toronto, Canada, this 29th day of January, 1897.

WILLIAM STEPHENSON.
